VENETIAN BLIND

Samuel J. Fisher, Washington, D. C.

Application October 26, 1933, Serial No. 695,352

9 Claims. (Cl. 156—17)

This invention relates to venetian blinds, and, more particularly, to improvements in the reinforced head suspension means and operating mechanism of this type of blind.

5 An object of the invention is to provide a suspension bracket for all venetian blinds which will adequately support the blind, hold the same in adjusted position and from which the entire assembly may be readily removed.

10 Another object of the invention is the provision of a bottom rail for the blind which will support the major weight at all times, and hold the blind against movement when subjected to gusts of wind.

15 A still further object of the invention is the provision of means for raising or lowering the blind by the actuation of a single cord.

A still further object is to so hold the blind slats that they may be readily removed from the 20 tapes and to insure easy assembly of the slats.

A further object is to provide means for closing the slats by a tipping bar and for holding the slats rigidly in open or closed position.

In the drawings, Fig. 1 is a front elevation of 25 the blind supported in a window frame.

Fig. 2 is a side elevation taken on line 2—2 of Fig. 1.

Fig. 3 is a detail sectional view of the bottom rail taken on line 3—3 of Fig. 2.

30 Fig. 4 is a vertical section of the hanger bracket taken on line 4—4 of Fig. 1.

Fig. 5 is a similar view taken on line 5—5 of Fig. 1.

Fig. 6 is an enlarged detail of the hanger 35 bracket and cord lock.

Fig. 7 is an enlarged detail of one of the pulleys.

Fig. 8 is a horizontal sectional view taken on line 8—8 of Fig. 3.

40 Fig. 9 is a side elevation of the bracket hook per se.

Fig. 10 is a front plan view of a venetian blind operated by a single cord.

Fig. 11 is an enlarged sectional view of a modified form of the bottom rail.

Figs. 12 and 13 are detail views of the tape suspending means.

Referring to Fig. 1, reference numeral 1 denotes a conventional venetian blind having slats 2 held in spaced relation by tapes 3 attached to and suspended from arcuate metallic members 4 which are supported in spaced relation on rod 5. Attached to and depending from the window frame or casement 6 are screw threaded hooks 7 55 which encompass the horizontal rod 5. The hooks

7 lie in the openings between the sides of the arcuate members 4 (see Figs. 4, 5, and 6). These members 4 are hollow metal casings having side walls 8 and 9 with collars 10 projecting from their side walls adjacent the registering openings 11. Near the bottom edges of the arcuate sections are elongated apertures 12 through which the upper ends of the tapes 3 are secured.

As shown in Figs. 6 and 9, it is preferable to reinforce the shanks of the screw hooks 7 by incasing them in a two piece separable collar 13 which has horizontal offset base portions 14 for attachment by screws or the like to the window casement 6. These collars 13 are of great value as they prevent lateral movement of the hooks 15 and prevent the shanks of the hooks from being bent or fractured. The collars serve a further purpose, inasmuch as they are provided with an offset lug 15 which is screw threaded for the reception of set screw 16. Retained in frictional engagement with the lug 15 and pivoted on the set screw 16 is a segment or latch 17 having teeth formed on its curved bottom section which, when the arcuate member 4 is in position on the rod 5, meshes with corresponding teeth 18 formed on 25 the top of one of the side walls thereof.

As before described, the ends of the spaced vertical tapes 3 are retained in elongated slots 12. The free ends of the tapes are attached to the body portion of the tape by separable fasteners 19, or they may be stitched to the tapes, or, as shown in Fig. 6, the ends of the tapes may be closed loops through which a pin is inserted, said pin passing through holes 12a in the side walls 8 and 9 of the member 4. The slats 2 of the venetian blind are spaced and supported between the tapes 3 by means of connecting strips or webs 20. In manufacture, these connecting strips are woven integrally into the vertical tapes.

In the double cord type of venetian blind shown in Fig. 1, it is customary to pass down the operating cords through slots formed in slats 2 where the vertical cords normally restrain the slats and prevent any relative movement thereof. However, in the form of venetian blind shown in Fig. 10, 45 which uses only a single cord for lowering and raising the slats, no cord openings are formed therein. Consequently, the slats could move if some means were not incorporated to relatively tie the slats in place. This is accomplished by having additional cross pieces 21 lie across the top of the slats and fastened to the webs 3 by separable fasteners such as snap hooks 22.

Lying in the bottom loop of the tapes 3 is a fairly thick bottom rail 25 which is slotted 55

throughout its under surface for the reception of a retractable latch mechanism, shown in detail Figs. 3 and 11. Mounted in the sides of the window frame are vertical guides 26 which are composed of two sheet metal sections 27 bent in the form of a U. As clearly disclosed in Fig. 8, the sections are retained at their bases against the window framing by a cast rack-bar 28, while the opposite ends of the sections 27 are spaced to form a vertical slot 29. The sections 27 are held in fixed position by bracket angle pieces 30 attached to the window frame and sections 27 by any suitable securing means.

The bottom rail 25 for use with a double cord venetian blind is shown in Fig. 3. It will be seen that the end of the operating cords 31 pass down through slots in the slats, passing through openings 32 in the bottom rail. After passing over pulley wheel 33, which is positioned in the groove formed in the bottom rail and is affixed in the side walls of the inverted metallic trough member 34, the cords are affixed to eye 35. This eye 35 is the end of reciprocal rod 36. Between the eye and the major portion of the rod a swivel 37 is formed so that no tilting or rotary movement imparted to the slats and bottom rail can be transmitted to rod 36. The rod is aligned through guide 38 attached to the trough 34 and through opening 39 formed in the end of the trough and the end of the bottom rail. Spaced from the end of the trough is a pin 40 passing through the shaft 36. Encompassing the rod and bearing on guide 38 and pin 40 is a coil spring 41. The outer end of the rod 36 terminates in an enlarged locking dog 42 provided with a beveled edge so that under the tension of the spring 41 the dog 42 is always in engagement with a tooth of the rack 28.

Thus it will be seen that when it is desired to raise the slats of the blind, pull is exerted on the free end of the operating cord 31. Through pulleys attached to shaft 5, the pull is transmitted to the bottom rail where it first withdraws the dog 42 from the teeth 28 against the tension of the spring 41. Continued pull on the cords elevates the slats through the medium of the tapes to the desired adjusted position. Immediately upon the pull being relieved on the operating cords, the springs 41 urge the dogs outward to engage the teeth 28 to thus hold the slats in adjusted position.

To insure easy operation of the operating cords, it is preferable to mount pulleys 50 on the shaft 5 and to retain the pulleys in position by means of the strap loop 51 encircling the shaft. In assembly, the shaft 5 is inserted through the opening in one side of the arcuate member 4, after which the shaft is threaded through the pulley strap 51 and then through the opposite side of the member 4. The openings 52 in the pulley strap receive the hook 7 allowing the rod 5 to rest in the bottom of the hook. The whole assembly is prevented from lateral movement by the side walls 8 and 9 of the arcuate member.

If desired, at one end of the shaft 5 a cord locking pulley 53, of slightly different construction, is slipped over the shaft 5 and held in position by collars 54 which may be secured to the shaft by screws or the like. The strap loop 55 is slotted on each side and a reduced ended roller 56 is journaled therein. The roller 56 is normally urged into contact with the cord, passing over the pulley 53 by the tension member 57 so that the cord is normally held lightly against the periphery of the pulley. When it is desired

to raise or lower the blind, the operating cord or cords may be pulled away from the pulley 53, which will relieve the tension of the locking roller 56, and permit the cords to be raised or lowered.

The single cord type of venetian blind disclosed in Figs. 10 and 11 is hung on hooks 7 and shaft 5, as is the double cord type; the major differences between the two types being the bottom rail structure, the use of pulleys in the top of the side guides, and the use of only one continuous operating cord.

In the single cord type, the bottom bar is underslotted, as before mentioned, and mounted adjacent each end thereof is reciprocating hollow squared tubular member 60, the outer end of which is solid and beveled at 61 to engage the teeth 28 of the guide. To insure proper movement of the member 60, it is centered and supported on upper and lower sets of rollers 62 journaled in the sides of the bottom bar. The end opening 63 is fitted with a separable bushing 64 having a squared opening 65 through which member 60 slides. To constantly urge the beveled end 61 into engagement with the rack teeth 28, a coil spring 66 is fastened to the member 60 and the roller 63 journal plate 67.

Directly behind the beveled tip 61, the member 60 is cut away and a pulley 67 journaled in the sides of the cut away section. Adjacent the top of the guide 26 is mounted a pulley 69, spaced from but at the same height as pulley 68 on the end portion of the shaft 5.

The single operating cord 70 passes over pulleys 68 and 69, down the guide 26, under pulley 67, through the squared tubular member 60, over to 35 and through the opposite latching mechanism, up the opposite guide and terminates and is anchored at 71 in the top of the guide.

Thus, when the cord 70 is pulled, the latches in the bottom rail are disengaged from the latch teeth and the blind may be raised to any desired position. Immediately upon releasing the cord, the latches engage the latch teeth under the tension of the coil springs. To lower the blind from its adjusted position, it is merely necessary to pull downward on the cord 70 a slight degree to release the latches, whereupon the weight of the blind bearing upon the latches will keep them in retracted position permitting the blind to be lowered to any desired position.

As indicated by the dotted lines in Fig. 6, a semi-circular filler block or bar 80 may be fastened to the top of the rod 5 to fill in the greater portion of the space between the rod and the window frame. This bar or block is not only ornamental in appearance, but tends to eliminate the light rays coming into the room at this point.

While the slats 2 may be tipped or turned by pulling on the tapes 3, it is preferable to attach a tippling device to the end of the rod 5 so that the slats may be readily turned and lowered to insure that they will be held in their adjusted positions. This tippling or turning device may take the form of an elliptical or circular block 85 fitted over the end of the rod 5. Operating cords 86 pass over the top of the block 85 and are fastened on opposite sides thereof so that a down pull on either of the operating cords will turn the slats to either the right or left. Inasmuch as the bar 5 turns, and as this bar is in frictional engagement with the hooks, it will be retained in adjusted position. Furthermore, as the rod 5 turns it carries with it the arcuate members 4, the rack teeth 18 of which, 75

meshing with the teeth on the depending lug 17, positively insures the retention of the blind in any adjusted position. The spring surrounding set screw 16 bears against the pivot point 5 of 17 and thus prevents accidental movement of the lug.

Provision may be made for retaining the slats in alignment with relation to the guides 26 by affixing metallic extensions 87 to some of the 10 slats. These extensions ride in the vertical slot 29 of the guide and prevent the blind from bilowing when subjected to gusts of wind.

What I claim is:

1. A venetian blind, including a horizontal supporting bar, suspension means therefor, a plurality of spaced arcuate members positioned transversely on said bar, vertical tapes attached to the outer ends of said arcuate members, slats held between said tapes, spaced vertical guides adjacent the ends of said slats, a bottom bar at the lower portion of said tapes, said bottom bar having a retractable latch in each end section thereof extending into said vertical guides.

2. A venetian blind of the character described 25 in claim 1, wherein the retractable latches comprise hollow spring projected tubes passing through bushings set in the ends of said bottom rail, the said tubes terminating in enlarged and flattened bevel edged heads, said bevel edged 30 heads normally engaging rack teeth formed in the bottoms of said guideways.

3. In a venetian blind, a horizontal supporting rod, suspension means therefor, said suspension means comprising depending hooks, hollow arcuate members positioned on said rod and severally embracing said hooks, reinforcing collars surrounding the shanks of said hooks, depending lugs pivoted to said collars and contacting with said arcuate members.

4. In a venetian blind, a horizontal supporting rod, suspension means therefor, said suspension means comprising depending spaced open hooks, hollow arcuate members encompassing said rod and severally embracing said open hooks, reinforcing collars surrounding the shank portion of each hook, an offset formed on each collar and depending lugs pivotally connected to said respective collars and contacting with the arcuate portions of said arcuate members.

5. In a venetian blind, a horizontal supporting rod, suspension means therefor, said suspension means comprising depending open hooks, hollow arcuate members encompassing said rod

and embracing said hooks severally, and depending slat supporting tapes detachably secured to the said arcuate members.

6. In a venetian blind of the character described, including a horizontal top supporting rod, spaced transverse members attached to said rod, horizontal openings formed in the extremities of said transverse members, spaced vertical slat supporting tapes detachably secured through the said openings of the transverse members and means for raising and lowering said slats.

7. In an adjustable blind of the character described adapted to be hung in a window frame, comprising a horizontal rod mounted at the top of said window frame, depending transverse parallel tapes suspended from said rod, a plurality of normally horizontal slats retained between said parallel tapes, and open guideways attached to the sides of said window frame; means for raising and lowering said slats comprising a cord anchored adjacent the top of one of said guideways, a pulley located at the top of the other guideway, said cord passing downward of said one guideway and outward from the bottom thereof, through the lowermost slat into the opposite guideway and upward therethrough to and over said pulley whereupon tension placed on the unanchored end of said cord will raise the said lowermost slat.

8. In a blind for use in window frames, including a horizontal rod hung from the top of said window frame, vertical guideways attached to the sides of said window frame, spaced vertical parallel tapes suspended from said horizontal rod, spaced slats held between said tapes and a bottom rail in the lower portion of said tapes; retractable latches contained by said rail engaging and sliding in said guideways and means for raising said slats and rail, said latches being positively retracted by operation of said raising means.

9. In a venetian blind, a horizontal supporting rod, spaced transverse members attached to said rod, horizontal openings formed in the extremities of said transverse members, spaced vertical tapes detachably secured through the said openings of the transverse members, spaced slat supporting cross-tapes secured to said vertical tapes and parallel guard cross-tapes spaced slightly above said supporting tapes and detachably affixed to said vertical tapes.

SAMUEL J. FISHER.
